DELOSS A. DANFORTH, OF ELKHART, INDIANA, ASSIGNOR TO HIMSELF AND A. N. CHAMBERLAIN, OF SAME PLACE.

Letters Patent No. 89,205, dated April 20, 1869.

IMPROVEMENT IN SASH-OPERATOR.

The Schedule referred to in these Letters Patent and making part of the same.

To all whom it may concern:

Be it known that I, DELOSS A. DANFORTH, of Elkhart, in the county of Elkhart, and State of Indiana, have invented certain new and useful Improvements in Window-Sash Operators and Fasteners; and I do hereby declare that the following is a full, clear, and exact description thereof, reference being had to the accompanying drawings, making part of this specification, and to the letters of reference marked thereon, like letters indicating like parts, wherever they occur.

To enable others skilled in the art to construct and use my invention, I will proceed to describe it.

My invention relates to a peculiar arrangement of devices for operating and fastening window-sash, and consists in attaching to the upper sash a vertical rack, and to the lower sash a disk, having formed on its face a spiral thread, that engages with said rack, the disk being mounted in such manner as to be revolved by a crank; and also in supporting the upper sash by a pivoted hook, operated by a cord, so that the sash may be instantly released, when it is desired to lower it, but that it will be automatically fastened upon being brought up in place.

Figure 1 is a vertical cross-section through the centre of a window, having my device attached;

Figure 2, a cross-section of the rack on the line $x-x$ of fig. 1;

Figure 3, a face view of the threaded disk;

Figure 4, a vertical section through the middle of a window, provided with a modified form of my device, in which a rack and cog-pinion are used, instead of the disk;

Figure 5, an enlarged view of the pinion and its supports as used in the modification;

Figure 6, a cross-section of the rack used in the modification, taken on the line $y-y$ of fig. 4; and

Figure 7, a perspective view of a window, having my device applied.

A represents the upper, and

B, the lower sash, the former having secured to it, on the inside at the middle, the rack C, provided, at its upper end, with an inclined head, or hook, f.

Secured to the upper side of the window-frame is a pivoted, or hinged catch, I, also formed with a bevelled face, and on its back connected with a cord, i, passing up through a staple in the frame, and hanging down in front of the sash, and having attached to its lower end a tassel, all as shown in fig. 1.

This catch is so located as to catch over the hook f, when the sash is brought to the required height, and thus hold it securely up in place.

By pulling down on the cord i, the catch may be disengaged from the hook f, and the sash allowed to descend.

On the upper side of the lower sash is located a standard, or bracket, E, in the upper end of which is

mounted a shaft, provided, on the inner end, with a crank, a, and on the opposite end with a head, or disk, D, which has formed on its outer face a projecting spiral thread, as shown in figs. 1 and 3, which thread engages with the teeth on the rack C, as shown in fig. 1, so that by turning the crank, the disk will be revolved, and its thread taking hold in the rack, will cause the disk to rise, raising with it, the sash B, or, by reversing the motion of the crank, lowering it in a similar manner.

Thus, it will be seen, the sash may be quickly and easily raised to any desired height, and held at any point, as there is no tendency of the disk to run back, and thus allow the sash to fall.

If it be desired to lower the upper sash, this device answers equally well, it being only necessary to lower the lower sash B, if raised, and, by pulling the cord i, release the upper sash, when, by turning the crank in the proper direction, the upper sash may be lowered, more or less, as occasion requires, and, by raising it again to its highest point, the catch I will automatically engage with the head f, and thus secure the sash.

By bringing both sash to their normal positions, and turning the crank, until the threads on the disk bind hard, the windows may be locked, so as to prevent their being raised from the outside, without removing, or breaking the glass.

It is obvious that a cog-pinion to engage with the rack, instead of the spiral threaded disk may be used, the rack being also modified in detail.

It will be observed that the crank-shaft stands at right angles across the top of the sash, and is provided, on the outer end, with an ordinary cog, or spur-pinion, G, as clearly shown in figs. 4 and 5, which engages with the rack F, as shown in fig. 4.

This rack is, in cross-section, L-shaped, as seen in fig. 6, and, instead of projecting teeth, has punched through it, a series of slits, or holes, as shown in figs. 4 and 6, into which the teeth of the pinion G mesh or enter, and thus when the crank is turned, raise or lower the sash, according to the direction of its revolution, the rack being secured to the sash, so that the perforated, or toothed portion stands at right angles therewith, as shown in fig. 4.

Unlike the disk D, pinion G will not support the sash when the hand is removed from the crank, but will allow it to drop, unless means are provided to lock it.

To do this, I pass through the arm of the crank a sliding pin, or bolt, b, and connect with it, on one end, a spring, d, and pivot to the opposite end, on the outside of the crank, a cam, e, all as shown in figs. 4 and 5.

When this cam is turned over in one direction, the bolt b is drawn back, as shown by red lines in fig. 5, and the crank is free to revolve, but when turned down in the opposite position, the bolt is drawn through by

the spring, and will strike against the standard H, which supports the crank-shaft, thus preventing the crank from revolving, and holding the sash in whatever position it may have been at the time the cam was turned down.

Thus constructed, I produce a strong, cheap, and effective apparatus for operating window-sash, which holds the sash at any desired point, and that a child may operate, and that operates either sash independent of the other.

Having thus described my invention,
What I claim, is—

The vertical rack C with hook f, in combination with catch I and disk D, provided with a spiral thread, all constructed and arranged substantially as herein described, to operate and fasten window-sash.

DELOSS A. DANFORTH.
